UNITED STATES PATENT OFFICE.

CONRAD HUBERT, OF NEW YORK, N. Y.

DESIGN FOR A LAMP-BODY.

SPECIFICATION forming part of Design No. 31,711, dated October 24, 1899.

Application filed August 18, 1899. Serial No. 727,706. Term of patent 14 years.

To all whom it may concern:

Be it known that I, CONRAD HUBERT, a citizen of the United States, residing in the city of New York, borough of Manhattan, county 5 and State of New York, have invented and produced a new and original Design for a Lamp-Body, of which the following is a specification, reference being had to the accompanying drawings, forming a part of this specification, 10 in which—

Figure 1 is a perspective view of the lamp-body. Fig. 2 is a top view thereof. As shown in the drawings, the leading and essential feature of this design consists in a 15 unitary lamp-body A, having the appearance of three cylinders grouped together, thereby producing a shape of trefoil outline in horizontal section, and a lamp-reflector B, of parabolic or conical form, attached by its apex to 20 the lamp-body.

The lamp-body, as shown, is so shaped that

three cylindrical batteries grouped side by side can be inclosed therein with a minimum of waste space. A handle C is attached to posts c on the cover a. The handle is preferably of trefoil outline to harmonize with the outline of the body. 25

The reflector is intended to inclose an incandescent lamp, and a glass or lens g covers the front of the reflector. 30

Having described my design, what I claim, and desire to secure by Letters Patent of the United States, is—

The design for a lamp-body, substantially as herein shown and described. 35

Signed by me in New York city, borough of Manhattan, State of New York, the 16th day of August, 1899.

CONRAD HUBERT.
